RAILWAY SWITCH

Filed March 31, 1923

2 Sheets-Sheet 2

UNITED STATES PATENT OFFICE.

JOHN A. VEAZEY, OF YOUNGSTOWN, OHIO.

RAILWAY SWITCH.

Application filed March 31, 1923. Serial No. 629,029.

To all whom it may concern:

Be it known that I, JOHN A. VEAZEY, a citizen of the United States, residing at Youngstown, in the county of Mahoning and State of Ohio, have invented certain new and useful Improvements in Railway Switches; and I do hereby declare the following to be a full, clear, and exact description of the invention, such as will enable others skilled in the art to which it appertains to make and use the same.

The invention has relation to railway switches which are locked both in open or closed position, thereby preventing accidental movement of the switch from either the open or the closed position, and in accordance with the present invention, the primary object is to prevent the derailment of a train by running into an open switch, means being provided whereby the switch is automatically closed, the locking mechanism being released by the weight of the train, or at least the locomotive, and the switch being thrown into closed position by the flange of a wheel as the same passes between the switch point and the adjacent main rail.

Other objects and advantages will be apparent and suggest themselves as the nature of the invention is understood.

While the drawings illustrate an embodiment of the invention it is to be understood that in adapting the same to meet different conditions and requirements, various changes in the form, proportion and minor details of construction may be resorted to without departing from the nature of the invention.

Referring to the accompanying drawings forming a part of the application:

Figure 1 is a top plan view of a railway switch embodying the invention.

Figure 2 is a vertical transverse section on the line 2—2 of Figure 1.

Figure 3 is an enlarged sectional detail view showing the relation of the parts when the switch is open.

Figure 4 is a similar view showing the disposition of the parts when the switch is closed.

Figure 5 is a sectional detail on the line 5—5 of Figure 2.

Figure 6 is a sectional detail on the line 6—6 of Figure 2, showing in dotted lines the cut away upper portion of the ties, and

Figure 7 is a detail section on the line 7—7 of Figure 2.

Corresponding and like parts are referred to in the following description and designated in the several views of the drawings by like reference characters.

The numeral 1 designates the rails of the main track and 2 the switch points, the latter being connected for simultaneous movement by means of a tie 3. A box 4 is slideable beneath the main rails 1 and is connected at one end by means of a link 5 with a switchstand 6 disposed at one side of the track and serving as convenient means for throwing the switch when it is required to operate the same by hand. The switch point tie 3 has a twofold sliding movement, the one with the box 4 and the other independently of the box and automatically operable by the train, whereby to throw the switch from open to closed position to prevent a casualty. Locking means are provided between the switch point tie 3 and the box 4 to cause both to move in unison when throwing the switch by means of the switch stand. These locking means consist of

similar dogs 7 and 7^a and a lock member 8, the latter being disposed within the box 4 to move longitudinally therewith and having an independent vertical movement. The dog 7 locks the switch in open position and the dog 7^a locks the switch in closed position. Both dogs do not operate at the same time and when one is in locking position, the other is released from the lock member 8. The lock member 8 is provided with an opening 9 for each of the dogs 7 and 7^a and the switch point tie 3 is provided with an opening 10 for each of said dogs. A keeper 11 attached to the tie 3 extends over the opening 10 and confines an expansible helical spring 12 normally urging the dog 7 or 7^a downwardly whereby to cause it to enter the opening 9 when in register therewith.

Expansible helical springs 13 interposed between the bottom of the box 4 and the lock member 8 normally support the latter in elevated position and admit of its depression whereby to clear the dog 7 to admit of the automatic throwing of the switch by the train, thereby preventing a casualty from

the train running into an open switch. A pin 14 extends upwardly from the bottom of the box 4 in position to engage each of the dogs 7 and 7^a and this pin limits the down-

ward movement of the dog so that when the member 8 is depressed, it clears the dog and admits of the switch points being automatically moved by the train. When the 5 switch is automatically thrown by the train from open to closed position, it is locked in the closed position by means of the dog 7^a.

To facilitate the vertical movement of the lock member 8 in the box 4, ball bearings 10 15 are provided and to facilitate the movement of the tie 3, ball bearings 16 are disposed between said tie and the lock member 8. The tie 3 is constructed as a cover to the box 4 and overhangs the same and is 15 provided with depending flanges 17. Openings 18 are formed in the bottom of the box to provide an escape for moisture.

In practice, the main rails 1 are mounted to move vertically under the weight of the 20 train and this vertical movement depresses the lock member 8 so as to clear the dogs 7 and 7^a, thereby releasing the switch which may be automatically thrown from open 25 position to closed position by a flange of the car wheel engaging a side of a switch point, and when the switch is closed it is automatically locked. The usual wooden ties 22 at each side of the tie 3, have portions of their upper surfaces cut away as indicated at 23 to permit the main rails 1 to move vertically under the weight of a 30 train, to depress the lock member 8.

The dog 7 locks at tie 3 to the member 8 and as the latter is movable with box 4 35 and the latter is coupled to the switch stand, it follows that switch may be thrown when required either to the open or closed position by means of the stand 6, the switch being locked in either position by locking 40 the operating member of the switch stand in any usual or preferred way.

The box 4 may be mounted in any preferred way and is directed in its movements by guides 20 secured to a tie let into 45 the road bed. Antifriction bearings 21 are interposed between the guides 20 and the box 4 to reduce the friction to the smallest amount possible. A lever 19 is mounted in a side of the box 4 in position to engage 50 a dog 7 or 7^a to admit of either dog being operated at will independently of the train.

What is claimed is:

1. In a railway switch, a manually oper-

able switch member, a train operable switch member mounted to move with the manually operable member and to have a movement independent thereof, and locking means between the two members and releasable by the weight of the train preliminary to the automatic throwing of the switch by the 55 train.

2. In a railway switch, a manually operable switch member, a train operable switch member mounted to move with the manually operable member and to have a movement 60 independent thereof, a lock member movable with the manually operable switch member and depressible by the weight of a train, and dogs carried by the train operable member and adapted to engage the said 65 lock member and releasable by the weight of the train when said lock member is depressed.

3. In a railway switch, a manually operable switch member, a train operable switch member mounted to move with the manually operable member and to have a movement independent thereof, a lock member movable with the manually operable switch member and adapted to be depressed by the 70 weight of the train, dogs carried by the train operable member and yieldably mounted, and elements carried by the manually operable member to coact with said dogs to prevent depression thereof 75 when the lock member is depressed to clear the same.

4. In a railway switch, a box adapted to be connected with the switch stand, a lock member movable with the box and adapted 80 to be depressed by the weight of a train and provided in its length with openings, a switch tie forming a cover for the box, dogs carried by the switch tie and adapted to enter the openings of said lock member, 85 and elements extending upwardly from the bottom of the box to engage said dogs and limit their downward movement to clear the lock member when the latter is depressed by the weight of a train.

In testimony whereof I affix my signature in presence of two witnesses.

JOHN A. VEAZEY.
